UNITED STATES PATENT OFFICE.

WILLIAM F. THOMPSON, OF PHILADELPHIA, PENNSYLVANIA.

NECKTIE-SUPPORT.

1,318,242.

Specification of Letters Patent.

Patented Oct. 7, 1919.

Application filed February 8, 1919. Serial No. 275,760.

To all whom it may concern:

Be it known that I, WILLIAM F. THOMPSON, a subject of the King of Great Britain, residing at 2110 Summer street, Philadelphia, in the county of Philadelphia and State of Pennsylvania, have invented new and useful Improvements in Necktie-Supports, of which the following is a specification.

10 The invention relates to apparel devices and more particularly to neck tie devices, and has for an object to provide a simple holder or support for a neck tie to secure the same in position at the front of a collar and 15 prevent undue sidewise or upward or downward movement thereof, and also secure and hold the tie in a graceful position relative to the collar.

The invention comprehends among other 20 features, the provision of a neck tie support which is preferably formed of a single piece of material suitably fashioned for attachment to the usual stud or collar button, which holds the collar at the front, the device by reason of its formation and disposition, holding the neck tie against any sidewise movement or from slipping up or down and also retaining the neck tie in a graceful position, it being understood that these 25 functions apply at the point where the knot of the neck tie is made, and which is usually at the front of the collar between the two outer flaps thereof.

In the further disclosure of the invention, 30 reference is to be had to the accompanying drawings, constituting a part of this specification, in which similar characters of reference denote corresponding parts in all the views, and in which,

35 Fig. 1—is a vertical sectional view taken through a collar and shirt with a neck tie, and my device shown in side elevation, the device being in applied position.

40 Fig. 2—is a front elevation of the device. Fig. 3—is a side elevation thereof, and

45 Fig. 4—is a plan view.

Fig. 5—is a similar view showing the device applied, and,

50 Fig. 6—is a front elevation of a slightly modified form.

Referring more particularly to the views, the numeral 10 indicates a shirt, the numeral 11 the collar band thereof, and the numeral 12, a collar, a collar button 13 being 55 provided to pass through the collar band 11 at the front and also through the collar

12 to secure the collar in position on the shirt. A tie 14 of the usual four-in-hand variety, is shown applied to the collar in the usual manner.

60 My invention as set forth in Figs. 1 to 6 inclusive, comprises a single piece of material preferably a heavy grade of wire and indicated by the numeral 15, said piece of material being bent at its medial portion to 65 form a button receiving loop 16 and then bent to form stem portions 17 forming a shank, after which the piece of material has the portions 17, bent in opposite directions upon themselves to form upwardly extending sides 18 which terminate in downwardly 70 projecting arms 19, the termini of which are bent upwardly and inwardly to form gripping elements 20. By reference to Fig. 3, it will be seen that at the point of formation of the side portions 18 with the stem portions 17, said side portions 18 are bent slightly backward or rearward so that the 75 loop 16 and shank formed by the stem portion 17 will lie in advance of the sides 18, 80 this formation being also shown in the plan view in Fig. 2.

Now by reference to Fig. 1 it will be seen that in applying the device, the same is sprung 85 over the projecting front end of the collar button 13 and then suitably manipulated to bring it into a position immediately behind the knot 14^a, of the tie. It will be noted that in this operation, the rear faces of surfaces 90 of the sides 18, pressing against the collar 12 together with the engagement of the loop 16 with the collar button, will force the loop 16 and stem portion 17, rearwardly into the vertical plane of the sides 18 and this operation causes gripping elements 20 to be moved 95 closer together so that the pointed portions thereof will grip into the tie and thus hold the same rigidly. This operation is clearly shown in Figs. 1, 4, 5, and on reference to Fig. 4, it will be seen that when the device is 100 by itself the gripping elements 20 are spaced a certain distance apart, whereas the application of the device to the collar button and collar, will move said gripping elements closer together, as clearly set forth in 105 Fig. 5.

With this device it will be seen that the tie will now be held against any side-wise movement and also be held from slipping upwardly or downwardly relative to the collar; further the device will effectively hold 110 the knot of the tie in a sort of forwardly

bulging position, which arrangement is found to be highly desirable, particularly in connection with certain forms and shapes of collars, thus greatly enhancing the appearance of the tie when it is in place.

In Fig. 6 I show a slightly modified form of my invention, in which instead of having only one loop 16, I form a blank to form a plurality of loops 16^a, 16^b. With this arrangement the tie can be secured toward the lower portion of the collar or if desired, can be held near the top portion of the collar, and it will be noted that I also disclose in Fig. 6, slightly different forms of gripping elements 20^a, which instead of terminating in pointed portions are formed with knobs 20^b.

From the foregoing description it will be clearly apparent that the tie support described can be cheaply manufactured, being

formed of a single piece of wire-like material, and that it can be readily applied to effectively accomplish the purpose for which it is desired.

Having described my invention, I claim,— 25

As a new article of manufacture, a neck tie support comprising a single piece of material bent at its medial portion to form a loop, and having portions bent downwardly to form a shank, said piece of material then being bent upon itself slightly rearward to form side portions extending upwardly and then bent forwardly and downwardly to form arms terminating in upwardly and slightly relatively inclined gripping elements. 30 35

In testimony whereof I have affixed my signature.

WILLIAM F. THOMPSON.
